UNITED STATES PATENT OFFICE.

GEORGE E. HAWES, OF BRIDGEPORT, CONNECTICUT.

CORSET-STAY.

1,022,364.

Specification of Letters Patent.

Patented Apr. 2, 1912.

Application filed December 2, 1910. Serial No. 595,200.

To all whom it may concern:

Be it known that I, GEORGE E. HAWES, citizen of the United States, and resident of Bridgeport, in the county of Fairfield and State of Connecticut, have invented certain new and useful Improvements in Corset-Stays, of which the following is a specification.

This invention relates to certain new and useful improvements in stays for corsets, garments and the like, and consists in certain improvements in the construction thereof whereby a very much improved form of stay is produced.

The invention further refers to that particular class of corset stays which are formed of interwoven or coiled spring wire and comprising a relatively broad, thin flat spring stay that is very flexible and adapted to readily and uniformly bend in both a transverse and a lateral direction.

It is the purpose of my invention to reinforce, strengthen and stiffen such portion of a woven wire or other form of flexible corset stay, that is subjected to the greatest strain or abuses, thereby rendering the same more durable and lasting; particularly to reinforce and strengthen the center portion of the stay or that portion which when the stay is nested in a corset would represent the waist line, and to so construct and arrange said reinforcement as to form a flexible stay which is stiffest at its central portion and which stiffness is of a graduated character that grows less toward the end of the reinforcement, forming those parts more flexible than the said central part; further to construct and apply said reinforcement in a way which will not objectionably thicken the said stay or materially add to its weight and cost of production, and finally to generally improve upon the construction of a flexible corset stay in a way to produce a neat, attractive and effective stay as will later be more fully described.

With these and other objects in view the invention consists in the construction and novel combination and arrangement of parts hereinafter fully described, and illustrated in the accompanying drawings, and pointed out in the claims hereto appended, it being understood that various changes in the form, proportion, size, and other minor details of construction within the scope of the claims may be resorted to without departing from

the spirit or sacrificing any of the advantages of the invention.

Similar characters of reference denote like or corresponding parts throughout the several figures of the accompanying drawings forming a part of this specification, and upon which,

Figure 1, represents a side elevation of my improved corset stay complete in its normal position, and a laterally bent position of the stay in dotted lines. Fig. 2, is a side edge view of Fig. 1 and also having indicated by dotted lines, a sidewise bent position of the stay. Fig. 3, represents a side view of a portion of a woven wire corset stay with a portion of my reinforcing strip partially applied. Fig. 4, is a somewhat similar side view of the partially wound sheet metal reinforcing strip, which more clearly illustrates its construction of overlapping the extended edges and, Fig. 5, is a broken plan view of one of the sheet metal reinforcing strips to be applied to the stay.

While my invention is perhaps better adapted to be applied to various forms of woven wire corset stays yet it can be used in connection with other forms of stays with improved results. I prefer, however, to use it in connection with such a woven wire stay as is shown in the accompanying drawings and which is similar in all essential respects to that shown in Patent No. 501,221 and which is made of four distinct pieces of wire suitably coiled, assembled and pressed together to form a flat strip of a proper width and thickness to give the desired strength and rigidity, yet uniformly flexible in all directions.

Referring in detail to the characters of reference marked upon the drawings 10 indicates the main body portion of the corset stay which as will be seen is formed of wire, that is woven in a continuous piece and then cut to the desired lengths. The end portions are covered with a suitable sheet metal tip 11 of any desired construction. The steel 10 as thus far formed is similar throughout and possesses a like amount of flexibility at all points. This is true of all of the woven wire corset stays and as before stated my invention is equally applicable to all of the different designs.

My invention is adapted for the reinforcement of any part of a corset stay, yet in

the accompanying drawings I have shown it applied to the central part since that is the part where the greatest strain is usually applied and most necessary to protect. This 5 reinforcement is of a graduated character, being stiffer throughout its central portion and lighter and more flexible near the ends, thus producing a graduated form of stiffening, so that the ends will not be particularly noticeable when the stay is bent and consequently less liable to break at the point of end of reinforcement.

The reinforcement comprises a special form of thin sheet metal strip 12 which as 15 cut includes one plain straight edge 13 and an opposite serrated edge forming extensions that are alternately disposed flat and longitudinally against the opposite sides of the body of the stay when the strip is spirally wound around the stay, as shown in Figs. 1, 2, and 3.

The reinforcing strip is spirally wound around the body of the stay with its plain end portions 15 disposed to form the end 25 portion of the reinforcement while the remaining portion having the extensions are similarly wound to form the intermediate and stiffer part. The extensions 14 are thus omitted from the edge of the end portions 30 of the strip so as not to form any overlap of the metal, with the last wrap or two of the strip, as indicated at 15, thereby lessening the amount of stiffness at those two points adjoining the wire body of the stay 35 better to afford a graduated bend of the complete stay and thus avoid any tending of the stay to form a sharp bend and break at that point where pressure is applied.

The parallel adjacent edge portions of the 40 wound reinforcing strip are spaced apart as seen at 16 to insure an edgewise bend of the stay while the lower edge of the strip serves to overlap the extensions on the opposite sides.

45 After the thin metal reinforcing strip is spirally wound around the body of the stay with its lower straight edge portion 13 overlapping the extensions 14 of the top edge and the two free ends of the strip disposed flat against the side of the wire, the 50 said reinforced portion of the stay is placed in between suitable closing dies which serve to swage and crowd the thin sheet metal close against and in between the woven wire 55 for the purpose of effectively securing the strip to the stay and to further shape that part of the stay to better conform to size and shape of the outer end portions. After the stay has been constructed and formed 60 in accordance with the foregoing descrip-

tion, the same may be covered with a paper or cotton covering, not shown, in the usual manner, to form a smooth finish for the stay if desired.

Having thus described my invention what I claim and desire to secure by Letters Patent is—

1. The combination with a flexible garment stay, of a reinforcement therefor comprising a sheet metal strip spirally wound around the portion of the stay to be stiffened, and having a series of extensions formed upon one edge and disposed against the two sides of the main body of the stay when wound thereabout. 70

2. The combination with a flexible garment stay, of a reinforcement therefor comprising a sheet metal strip spirally wound around the portion of the stay to be stiffened, and having a series of extensions on one edge of the central portion of the stay 80 that are disposed against the opposite sides of the central portion of the stay to make it stiffer at the middle than at the end portion of said reinforcement, and means for securing said strip and its extensions against the body of the stay. 85

3. The combination with a woven wire garment stay, of a reinforcement therefor comprising a sheet metal strip spirally wound around the portion of the stay to be stiffened and having underlapping extensions upon one edge of the center portion 90 of the strip so as to be stiffer at its center than at its end portions to insure a gradual 95 bend of the stay.

4. The combination with a flexible garment stay, of reinforcement therefor comprising a sheet metal strip spirally wound around the portion of the stay to be stiffened, and having a series of extensions upon one edge to form both overlapping and spaced edge portions to render the stay stiffer, yet flexible. 110

5. The combination with a flexible garment stay, of a reinforcement therefor comprising a sheet metal strip spirally wound around the portion of the stay to be stiffened, and having extensions on one edge that are disposed longitudinally against the 105 side face of the body of the stay and under the adjoining edge of the reinforcing strip wound around the stay. 110

Signed at Bridgeport in the county of Fairfield and State of Connecticut this 30th day of November A. D., 1910.

GEORGE E. HAWES.
